Patented Jan. 26, 1886.

UNITED STATES PATENT OFFICE.

GEORGE B. BRYANT, OF PHILADELPHIA, PENNSYLVANIA.

GRIPPER FOR CABLE RAILWAYS.

SPECIFICATION forming part of Letters Patent No. 334,845, dated January 26, 1886.

Application filed September 10, 1885. Serial No. 176,724. (No model.)

To all whom it may concern:

Be it known that I, GEORGE B. BRYANT, of Philadelphia, in the State of Pennsylvania, have invented a new and useful Improvement 5 in Grippers for Cable Railways; and I do hereby declare that the following is a full, clear, and exact description of the same.

My invention relates to grippers for cable railways, and is an improvement more particularly upon the form shown in the Letters Patent of the United States granted to me on the 19th day of May, 1885, and numbered 317,967.

In the accompanying drawings, Figure 1 is a perspective view of the device and its supporting-frame, the gripping-jaws being shown open and the supporting-roller for the cable being shown in position to hold the cable up. Fig. 2 is an end view of the gripper-bar, with the parts in position to grip the cable. Fig. 3 is a vertical section on line *x x* of Fig. 1, partly in side elevation, the gripper-jaw being open and the supporting-roller swung aside to allow the cable to drop. Fig. 4 is a horizontal section on line *y y* of Fig. 2, with the jaws open. Fig. 5 is a side elevation. Fig. 6 represents a section on line 2 2 of Fig. 5.

In the drawings is shown a frame, *F*, on which rests the side bars, *f f*, supporting the yoke *G* of the guide-block, in which the grip- 30 per-bar slides. The frame is provided with sleeves *g*, which are slipped over the axles of the car and form a steady bearing for the frame, but at the same time tend to stiffen the axles. The block *H*, in which the gripper-bar slides, 35 has horizontal flanges *h*, which project over and rest upon the yokes *G*, being beveled on the outer edges to conform to the hollow curve of the central part of the yokes. The yokes have curved slots 1 1, enlarged at their ends to 40 receive screw-bolts 2, which pass through the slots into the ends of the blocks. Under the heads of these bolts are washers 3, and when the bolts are screwed down they hold the block in position on one side or the other, as the case 45 may be, the parts being adjusted so that the horizontal flanges of the block bear upon the yokes. This construction allows the block, and with it the gripper-bar, to be swung from one side to the other, and to be held in proper 50 position to grip either the right-hand or the

left-hand cable. The gripper-bar is represented at *A*, and is preferably of steel in the form of a plate, its sides being parallel with the line of the draft. It slides freely in the elongated slot in the block. The block is cast 55 in a solid piece, and has a stud, 6, at one end, on which is pivoted one arm of the bell-crank lever 7, by which the gripper-bar is raised and lowered. The angle of this bell-crank lever is pivoted to the bar *A*, and the other arm 60 is connected to a rod or bar, 8, which extends to the front of the car, and is connected to mechanism within reach of the attendant and adapted to operate the bar within to raise or lower it. At the other end of the block is a 65 stud, 9, mounted on a removable cross-piece held to the flanges of the block by screws. In this lug is a frictional roller, 10, against which the edge of the bar *A* bears as it is moved up and down by the bell-crank lever at the other 70 end. The operation of the bell-crank lever causes the friction of the bar to be thrown mainly on the edge next to the removable stud, and this friction is taken up by the roller 10, set in that stud. To the lower end of the bar 75 *A*, on one side, is screwed or bolted a cast-metal plate, *a*, having ears 11, in which are the bearings of the bolt which serves as a pivot for the movable jaw *B*. This jaw carries the frictional rollers 12, that bear upon and grip 80 the cable in the manner explained in my afore- said patent; but in the present case, instead of trusting to the effect of gravity to remove the jaw from the cable when pressure is released therefrom, I have provided a spring, 13, lo- 85 cated between the jaw and the bar below the pivot bolt. The eccentric *C* also, which bears upon and forced in the movable jaw, is pivoted in arms 14, and is operated by a bar, 15, which is connected to a sliding bar, 16, 90 working in the slot in the bar *A*. The eccentric *C*, however, is of an improved form. In order to give it a broader bearing surface, I have made it thicker, and have slotted it mid- way through its periphery, as shown at 30, 95 and pivoted the working-arm in the slot. In a recess in the jaw is a roller having two bearing-surfaces, 17, adapted to the bearing-surfaces on the side of the slot in the eccentric *C*. This gives, besides broader bearing, an even 100

draft on the eccentric. The sliding bar which communicates motion to this eccentric is operated by a bell-crank lever, *d*, having its bearing end pivoted upon the bar *A*, and 5 worked by a rod or bar, *e*, running to suitable mechanism within reach of the attendant. The cable is gripped in the same manner as in my patent above mentioned; but in order to prevent the cable from coming in contact with the parts of mechanism above it 10 when it is in its ordinary position I form on one side of the lower end of the bar *A* a stud, $1\frac{1}{2}$, (one on each edge,) which projects across the space occupied by the cable when between 15 the gripping-jaws, so that the cable cannot rise above them or be injured by coming in contact with any sharp corners.

In my aforesaid patent is shown a spindle carrying a roller in front of the gripping-jaws 20 for the purpose of supporting the cable in its position between the jaws. For the purpose of adapting this to use on lines of cable roads having other cables running across them, I have made this spindle and its roller removable from its position beneath the cable. This 25 roller *K* is mounted upon a pivoted lever or arm, being pivoted on the forward edge of the grip-jaw. The arm *k* projects back on its bearing, as shown at *l*, and is connected by a 30 link, 18, to the lower arm of the bell-crank lever *m*, pivoted at its angle on the outside of the fixed jaw. The other arm is connected by a link, 19, to the arm 20 on the lower end of the bar *o*, which slides in a slot in the bar *A*, 35 and is operated by mechanism hereinafter described. The swinging arm *k* is reduced to form a spindle, on which is slipped the roller *K*, which bears against a shoulder, 21, on the arm. In order to give additional vertical support to the free end of the arm, I provide a 40 bracket, 32, the lower end of which is held by a bolt, on which the arm *k* is pivoted, and the other end is turned up and made with a hole, through which the spindle passes, so that the 45 roller is held between the shoulder and the upturned end of the bracket. Outside of the bracket I place upon the spindle a sleeve, 22, the upper surface of which is flush with that of the roller, to give an even bearing-surface for 50 the cable, the sleeve being tapering toward its outer end, so that it may pass readily under the cable. It is held upon the spindle by a set-screw. The spindle projects beyond the sleeve, and is in range with the bracket *g*, having inclined upper surface, on which the spindle or 55 sleeve rides when the arm goes into place under the cable. The bracket is on the forward edge of the lower end of the movable jaw of the gripper. In suitable brackets, *r*, on the 60 bar *A* are friction-wheels 23, which are arranged to bear against the inside of the conduit when the gripper is passed around curves. The slide *O* is worked by mechanism similar to that which works the gripper—namely, a 65 bell-crank lever, *s*, one arm of which is pivoted upon the bar *A* and the other arm piv-

oted to the rod or bar 24, which extends to mechanism within reach of the operator, whereby it is moved back and forth. The angle of the bell-crank lever is pivoted at 25 to 70 the upper end of the slide *O*.

The lateral adjustment or swing which is given to the gripper-bar is, as above stated, to be used in connection with duplicate cables. There is always the liability that the 75 cable, or some strands thereof, will break, and this causes delay and great embarrassment in the running of the road. I propose to arrange the two cables side by side, and they may run at equal or unequal rates. If running at unequal rates, the gripper may be shifted from the slower to the faster when the conductor on any car desires to make up time.

It will be apparent that there are three rods or bars, *e*, 8, and 24, which extend to the forward end of the car, and they are attached to suitable handles or levers, whereby the various mechanisms are operated.

For convenience of the attendant, I arrange mechanism whereby he can perform part of 90 the labor by operating treadles or foot-levers, and part by pulling the hand-lever. By this arrangement the experienced attendant is enabled promptly and certainly to operate the necessary mechanism to stop the car in any 95 emergency.

The rod or bar connected to the gripping mechanism extends to a foot-lever on the left side. The rod or bar connected to the raising or lowering mechanism runs to a foot-lever on the right side, and the lever which swings the cable-supporting arm is connected to a lever, 34, adapted to the right hand of the attendant, leaving his left hand free for operating the ordinary brake mechanism. I 100 have not illustrated all these connections, as they will be obvious to those skilled in the art.

Manifestly connections may be changed without material difference, though that which 110 I have indicated is the most convenient.

It will be observed that while the car is running the arm which supports the cable may remain in its position across the jaw and while the jaws are opened.

It will be apparent that great inconvenience 115 must arise in any attempt to oil the friction-rollers on the grippers or supporting-arms. In fact it is ordinarily impracticable. To remedy this, I cast the rollers with oil-cups in 120 their ends. These oil-cups have suitable passages for the oil to flow in regulated quantities in the bearings. I prefer to make them in accordance with Letters Patent granted to me on the 25th of April, 1876. A sufficient 125 amount of oil can be placed in the cups to allow them to run a long time, and the device renders it practicable to keep the rollers oiled. The cups are shown at 33.

In running the car it will be understood that 130 the lowering mechanism is operated only when the cable has been dropped and it is necessary

to pick it up, and this occurs only at the crossing or when the gripper is shifted from one rope to another.

I claim as my invention—

5 1. The frame supported upon the axles of the car, yokes G, resting upon the frame, a block, and the gripper-bar sliding vertically therein, a bell-crank lever pivoted upon the block and combined with mechanism for raising and lowering the gripper-bar, all substantially as described.

15 2. The yokes resting upon the frames and hollowed upon their upper sides, the block carrying the gripper-bar adapted to rest thereon, and screw-bolts passing through slots in the yokes and into the ends of the block, substantially as described.

20 3. In combination with the block and the gripper-bar, the bell-crank lever 7, pivoted on the lug, in combination with the friction-roller on the stud 9, substantially as described.

25 4. In combination with the fixed jaw, the movable jaw pivoted thereto, a spring between the two adapted to keep them apart, and a cam mechanism for pressing the pivoted jaw against the cable, consisting of the eccentric supported from the bracket-arms 14, and the lever 15, for operating the same, substantially as described.

5. In combination with the movable jaw, 30 the eccentric having its central slot, the connecting-bar 15, pivoted within the slot in the eccentric, and the roller pivoted in the jaw having two bearing-surfaces, substantially as described.

35 6. In combination, the pivoted arm k, and friction-roller mounted thereon, a mechanism consisting of a link, 18, bell-crank lever m, and sliding bar for swinging said arm k into and out of place, substantially as described.

40 7. The combination, with the pivoted arm, of the link 18, the bell-crank lever m, the link 19, arm 20, bar o, and the mechanism for operating the bar o, substantially as described.

45 8. The combination, with the swinging arm k, of the bracket 32, substantially as described.

9. In combination with the swinging bar and spindle, the bracket q, fixed to the movable jaw, substantially as described.

50 In testimony whereof I have signed my name to this specification in the presence of two subscribing witnesses.

GEORGE B. BRYANT.
